of the channel which is associated with the second base wall of the receptacle cover, and which channel is provided with a base wall, and which base wall is depressed down into the cover and which base wall is provided with a roof wall which is at a higher level on the cover than said recessed central portion thereof.

UNITED STATES PATENT OFFICE

2,601,937

RECEPTACLE COVER

Andrew Ottesen, New York, N. Y.

Application March 28, 1949, Serial No. 83,893

2 Claims. (Cl. 220—48)

1

This invention relates to new and useful improvements in receptacle covers, and, more particularly, the aim is to provide a novel and valuable cover adapted to be opened in an improved manner by the aid of a prying tool such as a screw driver, the back of a spoon, etc.

More specifically, the present invention proposes an improved structure for the receptacle cover whereby unintended distortion of specially shaped parts thereof will be prevented during severing of the cover.

Also, in a receptacle cover characterized by the inclusion of an annular channel inwardly directed toward the receptacle body, there is provided an improved receptor, constituted by said channel, for said tool, for facilitating the imparting to the tool of a prying action to effect a ripping through of the cover material by the aid of a scored or other weakened line running along the channel at a special location therein, and such a scoring line which can practicably be located at said special location, particularly when the anti-distortion means above referred to is present.

A feature of the improved channel-receptor is the association therewith of a buttressing structure constituted by a disk-like entity and forming an integral part of the cover established by a recession of the central portion of the cover, and the combination with such recession (indeed, as a result of its establishment) of a second innermost continuous or annular wall; and, preferably, in further combination with the just described structure, the inclusion of an extra member of trifling cost added to and included in the cover. Such extra member is essentially, for cost reduction purposes, and for inherent strength, mainly of uniplanar nature rather than mainly of ring, tube or sleeve characteristic.

Because of the inclusion of said recession and the inclusion of said second inner wall, an annular chamber is provided inwardly of and preferably concentric with the first-named channel; otherwise stated, a second annular channel is provided which, instead of having a base wall depressed down into the cover as in the case of said first-named channel, has a roof wall which is at a higher level on the cover than said recessed central portion thereof.

By virtue of the arrangement last described, said recessed central portion of the cover presents, surroundingly of the same, what may be called a second base wall bounded by a continuously circularly extended corner, this corner at the junction of said second base wall with said

second inner wall; so that said corner, either of itself, or with the already mentioned added member present, at or with the aid of said member, establishes a fulcrum relative to which the prying tool may be rocked, thereby to force inwardly, or toward the body of the receptacle, the bottom wall of the first-named channel, incidental to severing the material of the cover at said scored line.

2

10 For further comprehension of the invention, and of the objects and advantages thereof, reference will be had to the following description and accompanying drawings, and to the appended claims in which the various novel features of the invention are more particularly set forth.

15 In the accompanying drawings forming a material part of this disclosure:

Fig. 1 is a perspective view of a metal can provided with a cover constructed in accordance with the present invention.

Fig. 2 is a top plan view of Fig. 1.

Fig. 3 is a fragmentary enlarged vertical section, taken on the line 3—3 of Fig. 2.

Fig. 4 shows the parts of Fig. 3, after ripping the severable cover material in accordance with the invention.

Fig. 5 is a view similar to Fig. 3, but showing a modification of the new receptacle cover.

Fig. 6 is a view similar to Fig. 4, but in regard to the structure of Fig. 5.

Fig. 7 is also a view like Fig. 3, but showing a further modification of the new receptacle cover.

Fig. 8 is a view also similar to Fig. 4, but in regard to the structure of Fig. 7.

Referring now in more detail to the drawings, and first to Figs. 1-4, a conventional form of receptacle body is indicated at 10, and its cover, generally, at 11.

40 The cover 11 is formed to include an inwardly directed channel 12 having an outer wall 13 which continues into a base wall 14 which continues into an inner wall 15. A score line 16 is arranged in conjunction with the channel 12 in the vicinity of the junction of the inner wall 15 with the base wall 14 of the cover. These are some of the essential parts of the improved cover.

45 It is intended that the cover be engaged upon the top of a receptacle, such as the receptacle 10. This engagement may be accomplished in the usual way by the double seam shown.

It is to be noted that the said score line 16 is at the bottom of the channel 12, and at or very near the junction of the base wall 14 and the inner wall 15 of said channel.

Also, according to the present invention, in addition to the elements 12-16, the cover 11 is shown as having the already mentioned recessed central portion, or the aforesaid second base wall, this shown at 17; the already mentioned second-named annular channel for providing the aforesaid annular chamber 18 topped by a roof wall; the already mentioned second continuous annular wall, as shown at 18^a; and the already mentioned continuous circularly extended fulcrum-providing or assisting corner, as shown at 19.

When a prying tool of the kind above mentioned or of any article conveniently at hand, is at its end to be its working end inserted into the channel 12 of Fig. 3, and then rocked in a clockwise direction in that view, the cover material at the score line 16 gives, and there is a breakthrough along said line, quickly and certainly; the annular walls 15 and 18^a now coacting with the main central recessed portion 17 of the cover to prevent distortion of the structure 15-18^a-18-17, it being noted that the degree of recession of said portion 17 is preferably considerably less than the degree of recession of the base wall 14 of the channel 12.

The already referred to fulcrum is located at 19. When a portion of the score line 16 is severed and so a portion of the length of the channel 12 is pried open, it is possible to insert the prying tool beneath such pried-open portion of the cover, past the torn line 20 turned away from which is a lip 21 which at or near its root limit bears against said corner 19. On now whirling the prying tool longitudinally of the channel 12, the lip 21 may be circularly extended to a point where it is very easy to tear out the central part of the cover.

The advantage secured by such coaction is the added fulcrum power to the prying tool.

Referring to the modification illustrated in Figs. 5 and 6, the parts to which are applied reference numerals with primes added correspond, respectively, to the parts to which have been applied the same reference numerals without primes. Here, it will be noted, the main central recessed portion 17' of the cover 11' is of even a less degree of recession than the degree of recession of the channel 12'. Also, the cover 11' includes an extra or added member, to wit, a disk 22. As will be noted from Fig. 6, the aforesaid fulcrum corner is now directly coincident with the periphery of said disk, although the corner last named is, as it were, backed up by a corner 19' corresponding to the corner 19.

Referring to the form of the invention shown in Figs. 7 and 8, the parts to which are applied reference numerals with double primes added correspond, respectively, to the parts to which have been applied the same reference numerals without primes. Here, the main central recessed portion 17'' of the cover 11'', is shown as of about the same degree of recession as the main central portion 17' of the cover 11'. In this arrangement, in substitution for the disk 22, there is provided an exceedingly shallow-cup structure 23, which can be readily stamped and drawn from thin sheet material; said structure 23 comprising a main disk-like central portion 23^a surrounded by an upturned annular skirt extension in the form of a very low wall 23^b, which wall, as shown, desirably, completely fills the chamber 18''.

While I have illustrated and described the pre-

ferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a receptacle cover having a recessed main central portion bounded by an upstanding wall continuing into a circumferential inwardly directed channel having an inner wall and a base wall, a score line in the channel at the junction of the inner wall and the base wall along which the cover can be broken open, a cup-like structure reinforcing the recessed main central portion and the upper portion of the inner wall of the channel, said cup-like structure comprising a main disk-like central portion secured to the inner face of the recessed main central portion, said disk-like central portion being of a diameter corresponding to the diameter of the inner periphery of the inner wall, and an upstanding wall continuing from the inner periphery of said disk-like central portion with its outer periphery in contact with the inner periphery of the inner wall.

2. In a receptacle cover having a recessed main central portion bounded by an upstanding wall continuing into a circumferential inwardly directed channel having an inner wall and a base wall, a score line in the channel at the junction of the inner wall and the base wall along which the cover can be broken open, a cup-like structure reinforcing the recessed main central portion and the upper portion of the inner wall of the channel, said cup-like structure comprising a main disk-like central portion secured to the inner face of the recessed main central portion, said disk-like central portion being of a diameter corresponding to the diameter of the inner periphery of the inner wall, and an upstanding wall continuing from the inner periphery of said disk-like central portion with its outer periphery in contact with the inner periphery of the inner wall, the upstanding wall of the recessed main central portion being spaced from the inner wall a distance equal to the thickness of said upstanding wall of said cup-like structure so that the outer periphery of the upstanding wall of the recessed main central portion is in contact with the inner periphery of said upstanding wall of said cup-like structure.
